UNITED STATES PATENT OFFICE.

RUSSELL R. JOHNSTONE, OF WAUWATOSA, WISCONSIN.

DESIGN FOR AN ADVERTISING-SIGN.

57,348.

Specification for Design.

Patented Mar. 15, 1921.

Application filed August 18, 1920. Serial No. 404,389. Term of patent 7 years.

To all whom it may concern:

Be it known that I, RUSSELL R. JOHNSTONE, a citizen of the United States, residing at Wauwatosa, in the county of Milwaukee and State of Wisconsin, have invented a new, original, and ornamental Design for Advertising-Signs, of which the following is a specification, reference being had to the accompanying drawing, forming part thereof.

The figure is a view in elevation of an advertising sign, showing my new design.

I claim:

The ornamental design for an advertising sign, as shown.

Signed at Milwaukee this 24th day of July, 1920.

RUSSELL R. JOHNSTONE.
